LIQUID LEVEL DIFFERENTIAL SENSING DEVICE

Carl H. Nordell, Crystal Bay, Nev.

Carl H. Norden, Crystal Bay, Nev.
Filed Sept. 7, 1962, Ser. No. 222,917

4 Claims. (Cl. 210—107)

The invention relates to a liquid level differential sensing device, and is particularly concerned with a control switch operable in response to the liquid level differential across the screen of a comminuting device positioned in a flowing stream of sewage or other liquid containing solids to be comminuted, to start and stop operation of the comminuting device.

The present invention provides means for starting and stopping the motor of a comminuting device of the type referred to, so that it will operate only when the operation is warranted by an accumulation of solids on the upstream surface of the screen.

In general, comminuting devices of the type referred to comprise a screen, a cutting cylinder rotatably mounted in association with the screen, a motor for rotating the cutting cylinder, and means for moving the cutting cylinder across the upstream surface of the screen. The screen and comminuting device are positioned in a stream of sewage or other liquid and the screen serves to intercept solids from the liquid stream flowing through the screen, and the cutting cylinder cooperates with the screen and/or with a comb adjacent the cutting cylinder to comminute the intercepted solids so that they can flow through the screen along with the liquid.

Installations having a heavy flow of sewage require constant operation of the comminuting device, but in many cases the flow of sewage is irregular and there are periods of very low flow when operation of the comminuting device is not required. The present invention is of particular advantage in connection with installations where the continuous operation of the comminuting device is not necessary. The invention provides control means to actuate a switch for starting the motor of the comminuting device when the solids intercepted by the screen block the flow of liquid through the screen to such an extent that the liquid level on the upstream side of the screen is raised a predetermined distance above the liquid level on the downstream side of the screen. As said solids are comminuted, the flow of liquid through the screen increases until the difference in liquid levels on opposite sides of the screen substantially disappears. When the liquid level becomes the same on both sides of the screen, the control means opens the switch to stop the motor of the comminuting device.

The control means of the present invention consists essentially of a diaphragm controlled switch that is actuated in response to a pressure differential that is caused by differences in the liquid level on the upstream and downstream sides of the screen of the comminuting device. The switch is opened to stop the motor of the comminuting device when the liquid level is approximately the same on both sides of the screen. Stopping the motor of the comminuting device whenever its operation is not required extends the useful life of the motor and the comminuting device. The control operates continuously to start the motor whenever operation of the comminuting device is required and to stop it whenever operation of the comminuting device is not required.

The structure by means of which the above noted and other advantages of the invention are attained will be described in the following specification, taken in conjunction with the accompanying drawings, showing a preferred illustrative embodiment of the invention, in which:

2

responsive control unit, with the cover of its cabinet removed;

FIG. 2 is a vertical sectional view of the control unit, taken on line 2—2 of FIG. 1, showing parts in elevation, 5 and illustrating schematically a commutating device and the conduits on opposite sides of the screen which form a part of the control unit;

FIG. 3 is a cross sectional view of the diaphragm switch control assembly shown in FIG. 1;

10 FIG. 4 is a cross sectional view taken on line 4—4
of FIG. 3;

FIG. 5 is a fragmentary detail sectional view taken along the line 5—5 of FIG. 3; and

FIG. 6 is a fragmentary detail sectional view similar to FIG. 5, showing the switch in open position.

Referring to FIG. 2 of the drawings, the control unit is mounted in a cabinet, generally indicated at 10, and is connected, in a manner hereinafter described, to a pair of rigid conduit sections 11, 12. The rigid conduit sections are arranged one on each side of the screen of a comminuting device 13 that is driven by a motor 14. The screen (not shown) is mounted in the frame 15 of the comminuting device 13. As shown, conduit section 11 is located on the upstream side of the screen, and conduit section 12 is located on the downstream side. These conduit sections are mounted securely in vertical position and each has an open bottom 16 and 17, respectively, equally spaced from the bottom 18 of the trough through which the sewage 19 or other liquid flows. The mounting is such that said open lower ends of the conduits are always submerged at the same level in the sewage 19 or other liquid being treated. Each rigid conduit section 11, 12, is connected at its upper end to the control unit by means of a flexible conduit section 20, 21, respectively.

35 Referring to the specific form of control unit illustrated, said unit includes a pair of conventional atmospheric pumps 22, 23, and a diaphragm-switch housing 24. A bracket 25 holds both pumps in cabinet 10. The housing 24, shown in FIG. 3, preferably comprises two externally flanged housing sections 26, 27, that are held together by screws 28 (FIG. 1). Housing 24 has a flexible diaphragm 29 secured between sections 26, 27. The diaphragm divides the housing into two chambers 30, 31, hereinafter referred to as the downstream chamber and the upstream 40 chamber, respectively. The diaphragm carries suitable washers 32 held against its opposite surfaces by a screw 33 which also serves to secure one leg 34 of a U-shaped bracket 35 against one washer for movement with the 45

diaphragm. Bracket 35 extends into the downstream chamber and loosely embraces a normally open micro-switch 36 supported on a bracket 37 mounted on the inside face of the related housing section 27. This switch is connected through a lead 38 to the electric circuit for starting and stopping operation of the motor 14 that drives the commutating device.

A tapped opening 39 communicating with upstream chamber 31 is connected by the flexible conduit section 20 to the upper end of the rigid conduit section 11, and a tapped opening 40 communicating with downstream chamber 30 is connected by the flexible conduit section 21 to the upper end of the rigid conduit section 12. Referring specifically to FIG. 1, the downstream conduit section 21 has a T-fitting 41 therein to which is connected a conduit section 42 leading from the compression side of atmospheric pump 22, the latter being provided with a pressure regulating knob 43. A similar T-fitting 44 and conduit section 45 connects conduit section 20 with the other atmospheric pump 23, having pressure regulator knob 46 thereon. The pressure regulator knobs 43 and 46 may be adjusted to cause the switch 36 to be

operated automatically at any desired pressure differential on opposite sides of the screen.

The atmospheric pumps 22, 23 are operated so as to maintain sufficient pressure in the conduits to cause air bubbles to escape continuously from the open bottom end of each conduit section 11 and 12. Each atmospheric pump is enclosed in a chamber having no outlet except the lowermost end of the conduit 42 or 45 communicating therewith, and the lower end of each conduit section 11, 12 is closed by a column of sewage or other liquid in which they are immersed. The pressure exerted by each pump to force air bubbles through its conduit depends upon the height of the liquid column in the lower end of said conduit. This pressure is exerted equally in all directions and tends to force the flexible diaphragm, which constitutes a portion of the wall of each chamber outwardly. When the height of the liquid column in the lower section of each conduit is the same, the pressure exerted by each pump is equal, and the diaphragm retains its normal position.

As solids intercepted by the screen accumulate on the upstream surface of the screen, the level of liquid 19 on the upstream side of the screen rises. This increase in the liquid level increases the height of the column of liquid in conduit section 11, and the pump connected to conduit section 11 is required to exert increased pressure to force the air bubbles through said conduit section. Since this increased pressure is greater than the pressure exerted against the opposite surface of flexible diaphragm 29, it moves the diaphragm toward switch 36. When the pressure differential is sufficient, screw 33, carried by the diaphragm, depresses plunger 47 to close the switch and thereby start operation of the comminuting device.

During the operation of the comminuting device, solids accumulated on the upstream side of the screen are comminuted, and, as the accumulated solids are comminuted, the flow capacity of the screen is restored to normal. As the flow capacity of the screen is increased, the difference between the liquid levels on opposite sides of the screen gradually diminishes. This ultimately results in diminished pressure in the upstream chamber 31 of the switch housing. When the pressure in chamber 31 has diminished sufficiently, the diaphragm 29 returns to its normal position. The upward movement of diaphragm 29, as viewed in FIG. 3, carries bracket 35 upwardly so as to move the leg 49 of bracket 35 into engagement with a reset button 48. The upward movement of reset button 48 shuts off motor 14 and thereby stops operation of the comminuting device. The electrical circuit is so arranged that operation of the comminuting device is stopped only when the cutting cylinder of the comminuting device is at the top of its travel.

The actuation of the switch 36 by the pressure caused by the difference in the liquid level on opposite sides of the screen insures operation of the comminuting device when the accumulation of solids on the upstream side of the screen is sufficient to require comminution, and prevents operation of the comminuting device when the accumulation of solids on the upstream side of the screen is not sufficient to require comminution.

Although I have described a preferred embodiment of the invention in considerable detail, it will be understood that the description thereof is intended to be illustrative, rather than restrictive, as many details of construction may be modified or changed without departing from the spirit or scope of the invention. Accordingly, I do not desire to be restricted to the exact construction described.

I claim:

1. A liquid level sensing device of a type responsive to variations in the liquid level of different portions of a body of liquid, said device comprising a diaphragm, a switch means mounted on said diaphragm for operating said switch in opposite directions, and two air pumps operable to move said diaphragm, said air pumps being connected to air escape conduits each of which has an

open lower end immersed in liquid and a column of liquid in the lower end portion of each of said conduits, the lower ends of said conduits being spaced equally from the bottom of said liquid, each of said air pumps being operated continuously to force a stream of air bubbles through the liquid in the lower end of the air escape conduit connected thereto, the greater height of the column of liquid in the air escape conduit immersed in the portion of said liquid having a higher liquid level causing the air pump connected thereto to increase the air pressure exerted by it to force air bubbles therethrough and thereby move said diaphragm in one direction against the pressure exerted by said other air pump, movement of said diaphragm a predetermined distance in either direction carrying said means into operative engagement with said switch.

2. A liquid level differential sensing device comprising a housing, a diaphragm dividing said housing into two separate chambers, a U-shaped bracket having two parallel legs, one of said legs being secured adjacent said diaphragm, said bracket being movable with said diaphragm, a conduit in flow communication with one chamber and opening into a body of liquid, a second conduit in flow communication with the other chamber and opening into a different portion of said liquid, means operable to maintain sufficient air pressure in each of said conduits to force a stream of air bubbles therethrough, said means being effective, when the level of one portion of said liquid reaches a predetermined differential relative to the level of the other portion of said liquid, to cause a sufficient differential in the air pressure in said chambers to displace the diaphragm, a switch mounted in one of said chambers between the parallel legs of said bracket, a compressible plunger projecting from one side of said switch and engageable by one of said legs, and a compressible reset button projecting from the opposite side of said switch, said plunger being operable by said diaphragm, when said diaphragm is moved in one direction, to close said switch, and said reset button being operable by said second leg of said bracket, when said diaphragm is moved in the opposite direction, to open said switch.

3. A liquid level differential sensing device comprising a housing, a switch enclosed in said housing, a diaphragm in said housing dividing the housing into two chambers, two switch actuating members projecting from one side of said diaphragm, two atmospheric pumps one being connected with each chamber, and conduits connecting each of said pumps with different portions of a body of liquid, each of said conduits having an open end immersed in one of said portions of liquid and forming a passage through which air forced from either of said chambers by its pump escapes into said liquid, said open ends of the conduits being disposed at the same level, thereby causing the pump connected to the portion of the body of liquid having the higher liquid level to increase the pressure in the chamber connected thereto, said pressure increase displacing said diaphragm, movement of said diaphragm to a predetermined distance in one direction carrying one of said switch actuating members into switch closing position, and movement of said diaphragm to a predetermined distance in the opposite direction carrying said other switch actuating member into switch opening position.

4. In combination with a comminuting device comprising a screen immersed in a stream of sewage for intercepting solids from said sewage, a cutting cylinder rotatably mounted for cooperation with said screen, and a motor for moving said cutting cylinder across the surface of said screen; a liquid level sensing device responsive to variations in the liquid level of said sewage on opposite sides of said screen, said sensing device comprising a diaphragm, a switch operable to energize said motor in closed position and to deenergize it in open position, means mounted on said diaphragm for opening

and closing said switch, and air pressure means operable to move said diaphragm, movement of said diaphragm a predetermined distance in one direction moving said first mentioned means to switch opening position and movement of said diaphragm a predetermined distance in the opposite direction moving said first mentioned means to switch closing position, said air pressure means including air escape conduits opening into said sewage on opposite sides of said screen.
